CARRIAGE FOR DISTRIBUTOR SPOUTS

Louis Delivuk, Spokane, Wash.

Application December 17, 1945, Serial No. 635,526

1 Claim. (Cl. 104—118)

2

1 This invention relates to a distributor spout mechanism and constitutes an improvement upon the spout mechanism covered by my patent issued June 3, 1941, and having Patent No. 2,243,840.

One object of this invention is to provide mechanism by means of which a spout for a grain elevator may be swung in a circular path and brought to a stop in position for delivering grain to a selected one of the bins of the elevator, the mechanism being driven by an electric motor and including as one of its elements a latch actuated by a solenoid which is in series with the motor so that when the motor is started the latch will be drawn to a releasing position and the solenoid de-energised when the motor is shut off so that it may secure the spout in a stationary position in registry with the inlet of a predetermined bin.

Another object of the invention is to provide a distributor spout mechanism having the motor and a gear casing mounted upon a bracket carrying the wheels which travel along a circular track extending parallel to the entrances of bins in a grain elevator.

Another object of the invention is to provide actuating mechanism wherein the motor and the solenoid for the latch may be controlled from a switch board located at a convenient point and the spout caused to move to a position for communicating with a predetermined bin by operating a selected switch of the switch board.

Another object of the invention is to provide an actuating mechanism for a distributing spout of a grain elevator which is compact and of simple and inexpensive construction.

The invention is illustrated in the accompanying drawings wherein:

Fig. 1 is a view in elevation of a distributing spout provided with the improved actuating mechanism.

Fig. 2 is an enlarged view showing the actuating mechanism in elevation and the spout in section.

Fig. 3 is a sectional view taken horizontally through the actuating mechanism along the line 3—3 of Figure 4.

Fig. 4 is a rear view of the actuating mechanism.

Fig. 5 is a wiring diagram.

This improved actuating mechanism for a distributing spout is employed as means for moving a spout into position for communicating with a predetermined bin of a grain elevator which may be of any height and construction desired and has its bins so arranged that their inlets extend in a circular path. The grain flows from

a hopper 1 into the upper end of the spout 2 which is pivotally mounted by a post 3 and its lower end is provided with an elbow or nozzle 4 which is downwardly curved so that when this nozzle is over the inlet 5 of a bin grain may flow from the spout into the bin. A circular track 6 is mounted upon the floor or platform 7 through which the inlets of the bin project, the inlets of the bins being arranged in a circular path extending about and in concentric relation to the track.

A block 8 which is formed integral with the upper end portion of the nozzle extends downwardly therefrom and has a depending arm 9 to which a bracket 10 is secured. The bracket has side extensions or arms 11 opposite which are the side portions 12 and 13 of a plate 14, the plate being secured against the bracket by bolts 15 which also secure the bracket to the arm 9 of the block 8. Wheels 16 and 17 are rotatably mounted between the side portions of the bracket and the plate by axles or shafts 18 and 19 and these wheels rest upon the track 6 along which they move when the spout is being swung from one bin to another. The shaft 19 extends into a gear housing 20 which is secured against the side portion 13 of the plate 14 by bolts 21 and within the housing or casing carries a gear 22 held fixed to the shaft by a set screw 23. An electric motor 24 is secured to the gear casing 20 by bolts 25 and the shaft 26 projects into the casing and carries a gear 27 which is fixed to the motor shaft by a pin 28 and meshes with the gear 22. The gear 27 is smaller than the gear 22 so that the shaft 19 is rotated at reduced speed and the spout swung easily from the inlet of one bin to another.

A block 29 projects from the outer or rear face of the plate 14 and is formed with a vertically extending groove or recess 30 which serves as a seat for a plunger or latch 31. The latch or plunger has its upper portion reduced to form a shank or stem 32 projecting upwardly through an opening at the top of the recess 30 and a spring 33 is coiled about the shank and urges the plunger downwardly so that its lower end portion normally protrudes from the bottom of the block. A plate 34 which is held to the block by screws 35 closes the outer side of the recess and prevents dislodgement of the plunger. A keeper 36 is located opposite the entrance neck of each bin and each keeper consists of a plate which rests upon the floor or shelf 7 and is provided along one side edge with an upstanding flange 37 through which bolts 38 are passed to secure the flange 37 against the confronting side face of the track 6.

A rib 39 projects upwardly from the base plate of the keeper and since this rib has sloping upper edge faces 40 between which is a notch or seat 41 the lower end of the plunger 31 may ride along an upper edge portion of the rib and engage in the notch to stop movement of the spout and hold it stationary with its nozzle aligned with the entrance of one bin. A solenoid 42 is secured against the outer side face of the plate 14 by screws 43 and the lower end of its core 44 is connected with the upper end of the plunger 31 by a bolt 45. The coil of the solenoid is connected in series with the motor 24 by the conductor 46 shown in Figure 5 and when a switch 47' of the circuit 47 is closed the plunger will be retracted and the motor set in motion. Therefore the wheel 17 will be driven and the spout swung in a circular path along the track 6 out of registration with the inlet of a bin with which it has been in position to deliver grain. The switch 47' is one of a number of such switches on a board 48 corresponding to the number of bins and each switch has associated with it an automatic cut-out of conventional construction for shutting off the motor as the nozzle approaches the inlet neck of a predetermined bin and the spout will coast along the track with the plunger in its extended position until the lower end of the plunger rides along a sloping upper edge 40 of the flange or rib 39 and enters the notch 41 to hold the spout against the further movement. In Figure 5 there has been shown a switch board designed for twelve switches, it being assumed that the elevator has twelve bins, and it will be understood that each of the twelve switches is hooked into the circuit 47 and is companion to one of the bins and the companion keeper. When it is desired to have the spout move to a certain bin it is merely necessary to close the switch companion

to this bin and the spout will be swung about the post 3 and moved along the track 6 until the bin is reached. The switch will then be opened and movement of the spout stopped by engagement of the plunger in the notch 41 of the keeper.

Having thus described the invention, what is claimed is:

Mechanism for moving a spout along an arcuate track from one position to another comprising a bracket adapted to be mounted vertically under a spout and supported against tipping movement thereby, a plate detachably carried by said bracket and having angularly extending side portions, side portions on said bracket and in spaced parallel relation to the first named side portions, wheels between companion side portions and mounted on shafts carried by said side portions, said wheels being positioned adapting them to rest upon the arcuate track, a transmission housing carried by said plate, said housing supporting a reversible power unit having a rotatable shaft extending into said housing, one of said wheel shafts extending into said housing, and power transmitting mechanism uniting said power unit shaft and said wheel shaft.
